Primary Examiner — Philip S Hyder(74) *Attorney, Agent, or Firm* — Christopher J. Scott(57) **CLAIM**

The ornamental design for the page turning device, as shown and described.

DESCRIPTION

FIG. 1 is a side elevational view of a page turning device; FIG. 2 is a bottom plan view of the page turning device; FIG. 3 is a top plan view of the page turning device; FIG. 4 is a first top perspective view of the page turning device; FIG. 5 is a first bottom perspective view of the page turning device; FIG. 6 is a second top perspective view of the page turning device; FIG. 7 is a second bottom perspective view of the page turning device in a condition of use; and, FIG. 8 is a third top perspective view of the page turning device in the condition of use. The broken lines in FIGS. 7 and 8 depict environmental subject matter and form no part of the claimed design.
